ROTARY PIVOTED HAMMER

Filed Jan. 17, 1927

Harold M. Plaisted.

2 Attorney

UNITED STATES PATENT OFFICE.

HAROLD M. PLAISTED, OF ST. LOUIS, MISSOURI.

ROTARY PIVOTED HAMMER.

Application filed January 17, 1927. Serial No. 161,551.

This invention relates to certain new and useful improvements in rotary pivoted hammers for crushers and pulverizers operating on coal, shale and other suitable material, 5 the peculiarities of which will be herein-after described and claimed.

The main object of my invention is to provide a rotary pivoted hammer having twelve grinding edges adapted to be adjusted successively in operative position, for use in crushers, pulverizers and like machines operating on coal, shale and other suitable material. Secondly, to provide means to effect such adjustment; and thirdly, to provide 15 means for effecting a shearing action by said operative edges successively.

In crushing and pulverizing hard abrasive materials, the wear on the grinding edge of a rotary pivoted hammer, incapacitates this 20 part of the hammer long before the eye or other part wears enough to make it inefficient. Hammers have been made with double edge and reversible on the hammer rod; also detachable tips or heads have been made 25 with two, four, six and eight grinding edges, respectively—each edge successively presented as the operative edge,—whereby several tips may be used successively on one shank before the latter requires to be replaced. 30 The grinding tip constitutes a small fraction of the cost of such a hammer, so that a very considerable saving in cost of operation is effected. These former tips are flat and thin, or are rectangular blocks, or triangular pyramids or other form, but are changed from their common simple form by 35 holes, recesses, notches, etc., for rivets, bolts, keys, clamps, etc., fastening such forms as modified for mounting on the hammer shank.

40 In the accompanying drawing on which like reference numerals indicate corresponding parts, Fig. 1 represents a front view of a hammer exemplifying my invention; Fig. 2, a side view of the same; Fig. 3, a side 45 view of the shank of such a hammer, with parts mounted thereon shown in section; Fig. 4, a detail view of the preferred form of my block having twelve grinding edges; Fig. 5, a plan view of Fig. 2; Fig. 6, a top 50 view of the shank only as shown in Fig. 3; and Fig. 7 a top view similar to Fig. 6, but showing means for effecting a shearing action by the operative edge of said block.

The numeral 1 designates the rectangular 55 shank of a rotary pivoted hammer provided with an opening 2 by which it is pivoted on

the usual hammer rod of a crusher or pulverizer. The operative edge of a pivoted hammer is located at the extreme distance from the pivot, and I have provided herein a 60 block having twelve grinding edges, each of which can be presented in such operative position by adjustable mounting of the same upon a shank. The preferred form of my twelve-edged block is that of a cube, the six 65 faces of which meet in twelve edges of substantially equal length and form right-angle grinding edges in the form illustrated herewith. I do not confine myself to a cube for my twelve-edged block but illustrate it 70 herewith.

I do not claim a cube simply per se, but as modified by intersecting through passages substantially as described.

Any suitable means for mounting my 75 block with twelve grinding edges upon the shank may be employed, but I have shown a preferred form as consisting of a base 3 at the outer end of the shank and having a stem 4 extending backward in the direction 80 of rotation of the hammer, so as to bring one of the grinding edges of said block into the position 5 for its operative position above described. The said stem is preferably cylindrical and I have provided corresponding 85 cylindrical passages 6 through the center of the block and intersecting at the center. Near the base of the stem are surfaces meeting to form angular projections 7 from the general contour of the stem and these projections are adapted to engage corresponding angular recesses in each face of the block that rests upon the base 3 in the various 90 adjustments. The stem is provided with a fillet 9 as shown in the drawing and a corresponding surface 10 is formed on the matching faces of the block.

Through the said stem, preferably in the plane of rotation 19, is passed a key 11 by means of a suitable keyway in the stem 100 which is preferably tapering backward as shown in Fig. 3. This key is provided at its front end with a guard-plate 12, integral therewith or otherwise, which covers the front face of the block except a portion 13 105 adjacent to the operative edge 5. The key is secured in position by a cotter 14 passing through an opening 15 at the rear end of the key which projects beyond a back plate 16 that guards the rear edges of the block. 110 The tapering key bears against the outer edge 17 of the keyway and holds the block

by the opposite edge of the key bearing against the lower portions 18 at each side of the said stem. These portions 18 are thus clamped by the key against the base-plate 5 by the reaction of the key against the outer face of the keyway in the stem between said portions, so that the block is wedged firmly against the base-plate. The angular projections near the base of the stem assist said 10 key in preventing rotary movement of the block on the stem, and maintain the operative edge in its preferred position at right angles to the plane of rotation 19, Fig. 1, and Fig. 6. The block may be readily adjusted 15 by withdrawing the key and raising the block from the engagement of the angular projections and then rotating it upon the stem axis 20. It is evident that the four grinding edges on the face of the block furthest from the pivot, can thus be rotated successively into the operative position 5, and maintained in such adjusted position by the key and angular projections before described. When these four grinding edges 20 just mentioned are worn, the block may be reversed upon the stem so as to bring the opposite face into the extreme position, and these four grinding edges by successive adjustments can be presented in the said operative position. In order to bring the remaining four surfaces into outer position so as to present the remaining four grinding edges in operative position, the block is removed from the stem and the stem is inserted 25 in an intersecting passage at right angles with the one previously used. This will allow of locating the block so that the faces that were temporarily the side faces (that is, connecting the top and bottom faces of the block in Fig. 2,) can be brought to the outer extreme position at the top of the stem, and by adjustment each of the remaining edges becomes the operative edge. In each adjustment the key passes through 30 the stem and one of the intersecting passages to maintain the operative edge in its adjusted position.

As before stated, the keyway through the stem is preferably in the plane of rotation 50 19. In Fig. 7 I show a keyway 17^a which is inclined to said plane and so are the corresponding angular projections at the base of the stem. My grinding block when mounted upon such a stem as just described, 55 will cause the operative edge to be inclined or slanting with regard to the plane of rotation as indicated by the dash line 5^a in Fig. 7. A shearing action is thus obtained by the grinding edge, in place of the presentation of the operative edge at right angles to said plane as indicated by dash lines in Fig. 6. The base-plate 3^a Fig. 7, is also 60 preferably slanted as shown, to agree with the slanting position of the grinding block on the stem.

I claim:

1. In a rotary pivoted hammer, a block having twelve grinding edges and intersecting through passages, substantially as described. 70
2. In a rotary pivoted hammer, a cubical block having twelve grinding edges and cylindrical intersecting through passages, substantially as described. 75
3. In a rotary pivoted hammer, a block having twelve grinding edges and intersecting through passages provided with surfaces forming angular recesses, substantially as described. 80
4. In a rotary pivoted hammer, a cubical block having twelve grinding edges and cylindrical intersecting through passages provided with surfaces forming recessed angles at each end, substantially as described. 85
5. In a rotary pivoted hammer, a cubical block having twelve grinding edges and six faces and multiple intersecting through passages, substantially as described. 90
6. A rotary pivoted hammer comprising a shank, an adjustable block having twelve grinding edges, and means to maintain each edge successively in operative position. 95
7. A rotary pivoted hammer comprising a shank, an adjustable cubical block having twelve grinding edges, and means to maintain each edge successively in operative position. 100
8. A rotary pivoted hammer comprising a shank having a stem at the top, a block having twelve grinding edges adjustably mounted on said stem and adapted to present each edge successively in operative position, and fastening means for said block in each adjusted position. 105
9. A rotary pivoted hammer comprising a shank having a stem inclined backward, a block having twelve grinding edges adjustably mounted on said stem, and means to secure said block on said stem in any adjusted position. 110
10. A rotary pivoted hammer comprising a shank having a cylindrical stem provided with projections near its base, a block having multiple grinding edges adjustably mounted on said stem and having recesses in each face adapted to engage said projections in any adjusted position of said block. 115
11. A rotary pivoted hammer comprising a shank having a stem provided with a keyway, an adjustable block having twelve grinding edges and intersecting through passages adapted to match said stem in any adjusted position, and a key passing through said stem and one of said passages in each adjustment of said block. 120
12. A rotary pivoted hammer comprising a shank having a base and stem with a keyway, a block having twelve grinding edges and intersecting through passages adjustably mounted on said stem and base and 125

adapted to present each edge successively in operative position, a backguard plate for said block, and a key provided with a front-guard plate for said block and adapted to 5 maintain said block in any adjusted position on said stem.

13. A rotary pivoted hammer comprising a shank having a stem provided with surfaces forming angular projections inclined 10 to the plane of rotation, a block having mul-

iple grinding edges adjustably mounted on said stem and adapted to present each edge successively in operative position and having angular recesses adapted to match said projections and slant the operative edge to the 15 plane of rotation in any adjusted position, substantially as described.

In testimony whereof I have affixed my signature.

HAROLD M. PLAISTED.
